UNITED STATES PATENT OFFICE.

HENRY P. RINDSKOPE, OF NEW YORK, N. Y.

BATHING-CAP.

1,139,312.

Specification of Letters Patent. Patented May 11, 1915.

Application filed May 8, 1914. Serial No. 837,192.

To all whom it may concern:

Be it known that I, HENRY P. RINDSKOPE, a citizen of the United States, and a resident of the city of New York, borough of Brooklyn, in the county of Kings and State of New York, have invented a new and Improved Bathing-Cap, of which the following is a full, clear, and exact description.

Among the principal objects which the present invention has in view are: to provide a cap of the character mentioned, which may be placed in wearing position and removed therefrom without disarranging the hair of the wearer; to provide a retaining device for a cap of the character mentioned, which may be installed without injuring the arrangement of the hair of the wearer; and to reduce the cost and simplify the construction of caps of the character mentioned.

20 *Drawings.*—Figure 1 is a side view of a cap constructed and arranged in accordance with the present invention, the same being shown in service position with the retaining device or band in relaxed or out-of-service position; Fig. 2 is a similar view, showing the band in service position; Fig. 3 is a front view in perspective, of a cap and retaining band therefor, constructed and arranged in accordance with the present in- 30 vention.

25 *Description.*—As seen in the drawings, the cap 8 is constructed from any suitable material, the requisite quality of which is that it shall be impervious to water. A popular form of cap heretofore has been that wherein some form of rubber or elastic material has been employed. This has been used for the reason principally that the lower edge or band of the cap has been used 40 to contract upon the head of the wearer, and thereby prevent the intrusion of water under the cap. This construction has, among other disadvantages, had the disadvantage that the head opening of the cap 45 requires the distention or expansion thereof to pass the hair of the wearer when the hair is arranged in the usual style. The disarrangement or confusion of the hair incident to placing the cap in service position has 50 been equal to, if not exceeded by, the effort required to remove the cap.

In the present invention, the above-mentioned difficulties are avoided by constructing the head opening for the body of the cap 8 sufficiently large to freely pass over 55 the hair as dressed or arranged. To retain the cap in service position, the elastic band or loop 9 is provided. The loop 9 is permanently secured to the cap, and preferably at the front thereof, under the knot 10 or 60 other suitable covering ornament.

The cap may be provided at the opening edge with a contracted band, or with a raw edge. The latter has been found to be the most desirable, as affording the least re- 65 sistance to the contraction of the loop 9.

As seen in the drawings, the operation of placing a cap such as indicated by the numeral 8, in wearing position, is to simply place the same over the head, the distention 70 of the opening in the cap being sufficient to permit this action without disarranging the hair of the wearer. When the cap is placed, the loop 9 is grasped and drawn downward to the nape of the neck, adjacent the edge of 75 the cap there located. When the loop is now released, it will be found that it contracts upon the head and the intervening cap, to hold the same firmly in wearing position. 80

Claims:

1. A bathing cap, having an enlarged head opening, and a resilient endless loop fixedly attached to a portion of the body adjacent the edge of the head opening there- 85 of and adapted to infold the remainder of the body.

2. A bathing cap comprising a full-opening body, and a contractile endless loop fixedly attached to said body adjacent the 90 edge thereof and adapted to extend over and contract upon the remainder of the body, to hold the same in contact with the head of the wearer.

3. A cap as characterized, having a con- 95 tractile endless loop, a portion of which is fixedly attached to the body, to form a contractile head band therefor.

4. A bathing cap comprising a body portion having an enlarged head opening, a 100 section of the edge of said opening being gathered for partly contracting the same:

and an endless elastic loop fixedly attached to said body portion and to the contracted section thereof, said loop being adapted to extend over said body portion for contracting the remainder of said head opening.

In testimony whereof I have signed my

name to this specification in the presence of two subscribing witnesses.

HENRY P. RINDSKOPF.
